(57) CLAIM

I claim the ornamental design for a pocket organizer, as shown and described.

DESCRIPTION

FIG. 1 is a rear perspective view of a pocket organizer showing the new design;

FIG. 2 is a front view of the pocket organizer;

FIG. 3 is a rear view of the pocket organizer;

FIG. 4 is a left side view of the pocket organizer;

FIG. 5 is a right side view of the pocket organizer;

FIG. 6 is a top view of the pocket organizer;

FIG. 7 is a bottom view of the pocket organizer; and,

FIG. 8 is a front perspective view of the pocket organizer shown in a state of use in a pocket of a user.

The dash broken lines showing the card and accessories in the figures and the areas within the broken lines depict environmental structure and form no part of the claimed design. The dot-dash broken lines showing the pocket of a user depict environmental structure and form no part of the claimed design.

1 Claim, 5 Drawing Sheets
